UNITED STATES PATENT OFFICE

FREDERICK A. BALLOU, OF NAYATT, RHODE ISLAND, ASSIGNOR TO B. A. BALLOU & CO.,
INC., OF PROVIDENCE, RHODE ISLAND, A CORPORATION OF RHODE ISLAND

COLLAR HOLDER

Application filed February 23, 1929. Serial No. 341,939.

This invention relates to a collar holder; and has for its object to provide a collar holder having jaws depending upon the inherent resiliency of the stock for forcing them into gripping position with the same so constructed as to allow the edge of the collar to be easily inserted between the jaws and yet firmly grip the collar when so inserted.

The invention further consists in the twisting of one of each pair of jaws of the holder to provide an entering space for the insertion of the collar into the jaw and at the same time provide a construction by which the jaw member may be easily moved against its inherent resiliency by the insertion of the edge of the collar into position between the jaws.

A still further object of the invention is to provide a neat appearance of collar holder of such a construction that the looped or coiled end of the jaw will be visible when the device is in collar attaching position.

With these and other objects in view, the invention consists of certain novel features of construction, as will be more fully described, and particularly pointed out in the appended claims.

In the accompanying drawings:

Fig. 1 is a top plan view of a collar holder of my improved construction.

Fig. 2 is a side elevation thereof with the body portion in section.

Fig. 3 is a top plan view of the body portion with the wire jaws removed.

Fig. 4 is a section on line 4—4 of Fig. 2.

A fashion or fad has arisen in the use of collar holding devices, whereby it has become popular to use a device having a safety pin appearance for holding the two spaced edges of the collar from spreading. Pins of the safety pin construction have been used to supply this fashion but as they cause a piercing of the collar they have been superseded by holders which have a pair of jaws to engage the collar on either side without piercing the same and in order that the holding device may have the appearance of a safety pin construction it has been customary to form the same out of wire, rolling or folding the ends into loop form to have the ap-

pearance of the loop which appears in the safety pin. It has been customary, however, in devices of this character to dispose the loop in a plane at right angles to the sheet metal surface of the base or at right angles to the surface of the collar gripped, in which position, it is found difficult to insert the collar between the jaws of the device. Further by disposing the jaws or loops at right angles to the surface of the collar, the coiled effect of the ends does not show and in order to avoid both of these undesirable effects, I have twisted or positioned the looped end of the jaw in a position at an acute angle preferably 45°, to the surface of the collar when engaged and to the surface of the sheet metal base portion of the device by which construction the collar may be more readily inserted between the jaws and yet the desired loop appearance of the device may be always visible in imitation of the safety type of construction; and the following is a detailed description of the present embodiment of this invention illustrating the preferred means by which these advantageous results may be accomplished:

With reference to the drawings, 10 designates the base or body portion of the device, which is formed of sheet metal cut out into the desired shape and roughened as at 11 at portions spaced from each end thereof. Openings 12 are pierced adjacent the middle of the device thru which a wire 13 is woven having a portion between the openings 12 disposed over the rear surface of the body 14 and extending thru these openings at a sharp angle thereto and thence over the surface 14 of the body portion to be rolled into loops 15 at either end thereof.

Each of the loops 15 has a portion 16 to engage the collar to be gripped, which portion is located to contact with the roughened portion 11 when the device is disposed in a plane inclined to the surface 14 of the body portion and also to the surface of the collar which may extend between the jaws 16 and the roughened portion 11 to form therewith an acute angle of substantially 45° as will be apparent from Fig. 4.

By inclining the loop 15, as shown, its

point of engagement with the body portion is offset from the longitudinal axis of the wire 17 extending over the surface of the body portion so that as the collar is inserted between the jaws the pressure of the collar may tend to rotate the loop as well as lift the same from the point where the jaw extends thru the hole 12 so that the jaw will separate from the body more readily than where no rotating action of the jaw is permitted. In this way a double yield in an upward direction as well as a rotary direction is afforded which enables the device to operate with much less effort and yet firmly grip the collar when inserted thereinto.

It will be further apparent that the inclined loop as viewed from Fig. 4, also serves as a guide to direct the collar to the point of nip between it and the base portion to additionally assist in the insertion of the collar into position.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A collar holder comprising a body portion for engagement with the under side of a collar, a clamping jaw mounted thereon for resilient movement towards and from said body portion for engagement with the upper side of the collar, said jaw rolled to generally form a collar engaging loop at its end, said loop being positioned substantially in a plane to make an acute angle with the surface of the collar gripped between it and the body portion.

2. A collar holder comprising a body portion for engagement with the under side of a collar, a clamping jaw mounted thereon for resilient movement towards and from said body portion for engagement with the upper side of the collar, said jaw rolled to generally form a collar engaging loop at its end, said loop being positioned generally to lie in a plane at substantially 45° to the surface of the collar gripped between it and the body portion.

3. A collar holder comprising a sheet metal body, a wire secured at its center to said body with its ends rolled to form loops and serve as jaws resiliently movable toward said body, the plane of said loops making an acute angle with the surface of said body.

4. A collar holder comprising a sheet metal body having a portion of its surface roughened, a wire secured at its center to said body with its ends rolled to form loops and serve as jaws resiliently movable toward said body, said loops being located to engage said body at the portion of its roughened surface and

the plane of said loop making an acute angle with the surface of said body.

5. A collar holder comprising a sheet metal body having a portion of its surface roughened, a wire secured at its center to said body with its ends rolled to form loops and serve as jaws resiliently movable toward said body, said loops being located to engage said body at the portion of its roughened surface, the plane of said loop making an angle of substantially 45° with the surface of said body.

In testimony whereof I affix my signature.

FREDERICK A. BALLOU.
